WATER CIRCULATING SYSTEM FOR WASH-
ING MACHINES

Thomas R. Sheetz, San Francisco, Calif.

Application February 14, 1935, Serial No. 6,562

4 Claims. (Cl. 141—9)

This invention relates to a water circulating system for washing machines and is an improvement upon my Patent 1,959,740, May 22, 1934.

The object of the present invention is the provision of a compact and efficient water circulating system particularly adapted for attachment to the container or tub of a washing machine wherein the washing liquid of the tub or container is circulated with sufficient force to thoroughly 10 cleanse the articles to be washed.

A further object of the invention lies in the design of the various parts going to make up the water circulating system which eliminates all excess in the number of parts used and reduces to 15 a minimum the parts necessary for the efficient operation of the circulating system.

Further objects of the invention are to provide a circulating system of the character referred to that is strong, compact and durable, 20 thoroughly reliable for its intended purpose, having very few parts that need repair, and that is comparatively inexpensive to manufacture.

With the foregoing and other objects in view, the invention consists of a novel combination, 25 construction and arrangement of parts as will be hereinafter more specifically described and illustrated in the accompanying drawings, wherein is disclosed the preferred embodiment of the invention, but it is to be understood that changes, 30 variations and modifications may be resorted to without departing from the spirit of the claims hereunto appended.

In the drawings wherein like reference characters denote corresponding parts throughout the 35 several views:

Figure 1 is an end elevation of a washing machine showing an adaptation therewith of a water circulating system in accordance with the present invention.

Figure 2 is a side elevation thereof, having parts broken away and showing certain of the parts in vertical section.

Figure 3 is a detailed vertical section of the article holding basket removed from the container or tub.

Figure 4 is an end elevation of the basket.

Figure 5 is a horizontal section of the drain valve taken substantially on line 5—5 of Figure 1.

Figure 6 is a bottom plan view of the discharge nozzle head.

Referring to the drawings in detail A denotes the substantially semi-cylindrical tub or container of the washing machine, preferably formed of metal and having an open top. The tub or 55 container rests on a pair of legs 11 at each end

and the upstanding sides 10 terminate in a curled flange 12 at the upper edge. On one of the sides 10 is a handle 13, which cooperates with a handle on the motor bracket, to be presently described, whereby the washing machine may be 5 moved.

It is within the contemplation of the present invention to stack the articles to be washed in the basket B and this basket fits in the tub or container A in spaced relation to the inner walls 10 thereof. The basket B is designed to conform to the shape of the tub or container A to allow a certain amount of rocking movement when assembled therein. The sides and bottom wall 14 are preferably formed of sheet metal and perforated so as to allow free circulation of water. The opposite end walls 15 are upright and preferably formed of sheet metal integral with the bottom and side walls. To support the side and bottom walls 14 and the end walls 15 there are 15 a pair of end frames 16 that are angular in cross section and the corners of the basket B fit in the angle of the frame and are secured thereto in any conventional manner. Spaced springs 17 extend across the interior of the basket B and 20 these springs are formed with hooks 18 on each end which hooks are trained through pairs of openings 19 in the end walls 15 whereby the springs are supported in the basket. There is 25 provided an excess of the pairs of openings 19 so as to provide interchanging of the position of the springs to accommodate the nature of the 30 articles supported in the basket during the washing operation.

The bottoms of the end frames 16 of the basket are formed with legs 20 to support the basket when it is removed from the tub or container A, while there are a pair of handles 21 secured to the frames for lifting the same.

To allow a certain amount of rocking movement of the basket B a pair of trunnions 22 are mounted on the end walls 15 and these trunnions are removably mounted in the U-shaped bearing brackets 23 on the inside of the tub or container A. Spaced rods 24 extend lengthwise of the basket and are secured at the opposite ends thereof by the screws 25 in lugs 26 on the end frames 16 to add additional lengthwise reinforcement to the basket B. The rods 24 are around the rim of the container. There is also a center rod 24a aligned with the trunnions 22 and held in position by the screws 22a which hold the trunnions 22.

To prevent water from splashing from the washing machine there is provided a cover which 55

includes a semi-cylindrical glass panel 25 the end edges of which are seated in channels 26 in the end rails 27 and the lower ends of these rails are provided with padded feet 28 that bear on the curled flange 12 of the tub or container A. This cover may be removed when loading or unloading the washing machine.

A casing 29 is secured to the lower part of the side 10 of the tub or container A. In the casing 29 is a drain passage 30 and an inlet passage 31. These passages 30, 31 at their inner ends register with an opening 32 in the side of the tub or container. Over the inlet passage 31 is secured a perforated plate 33 which strains the water being circulated. In the top of the casing 29 is an impeller chamber 34 that is open and the outer end of the inlet passage 31 registers with the center of the bottom of this impeller chamber. Casing 29 is formed with a lateral elbow 35 formed with a passage 36 with the inner end thereof opening into the sides of the impeller chamber 34. The elbow 35 forms part of the discharge conductor 55.

An elongated, horizontal disposed bracket 37 has a flange 38 on the inner end thereof secured to the side 10 of the tub or container A by means of screws 39. In an intermediate portion of the bracket 37 is a circular opening 40 which embraces and supports in a vertical position the motor housing 41 carrying the conventional electrical motor parts so as to rotate on a vertical axis. There is a depending neck 42 on the housing which terminates in a circular flange 43 and this flange 43 is secured by bolts 44 over the open top of the impeller chamber 34. Through the neck 42 is a bore 45 in which is rotatably mounted the armature drive shaft 46 which carries on its lower end the impeller 47 and the impeller rotates on a vertical axis in the impeller chamber 34. There is a counter bore 48 in the neck concentric with the bore 45 holding at its inner end the gland packing 49 pressed in position by one end of a coil spring 50 held by the cap 51 through which the shaft 46 extends. Should any water escape through the gland packing 49 there are a pair of radial ducts 52 in the neck above the gland packing to allow the water to escape.

The bracket 37 terminates laterally in a handle 53 which cooperates with the handle 13 for moving the washing machine from place to place. Between the handle 53 and the opening 40 in the bracket 37 there is an opening which supports the lower end of the discharge conductor indicated generally at 55. This discharge conductor 55 is formed of a lower conduit section 56 and the lower end of this section 56 is connected by the packed union joint 57 to the upper end of the elbow 35. At the upper end, conduit section 56 is formed with a socket 58 that receives the lower end of a right angled conduit 59. On the inside and at the top the socket 58 is tapered to receive the split metal ring packing 60 which is held in water tight position by the knurled nut 61 engaging with the threads 62 on the upper end of the socket 58. A packing washer 63 is interposed between the nut 61 and ring 60 to insure a water tight connection. Thus the discharge conductor indicated generally at 55 may be swivelled by loosening slightly the nut 61 when it is desired to load or unload the washing machine.

The outer end of the right angled section 59 of the conductor terminates over the open top of the tub or container A. The horizontal leg of

section 59 extends under the end rail 27 when the cover is on the tub or container A. On the free end of conductor section 59 is the nozzle 64 having a peripherally threaded neck 65 overlapping the free end of conduit section 59. The threaded neck 65 is secured by means of a screw 66 and on the end of the neck is a gland packing 67 held in position by the nut 68 thereby insuring a water tight connection. The bottom of the nozzle 64 flares outwardly as at 69 and is threaded on the inside as at 70 to receive the nozzle head 71 so that the nozzle head may be removed for the purposes of cleaning. On the opposite sides of the nozzle 64 are segmental shields 72 which act to deflect water into the tub or container and prevent the water from splashing over the sides thereof.

The nozzle head 71 is formed with a solid hub 73 and in this hub are preferably four inwardly tapering openings 74. Radiating from the hub 73 are baffle ribs 75 preferably being eight in number and spaced circumferentially to provide openings 76 between these ribs. The baffle ribs are disposed at an angle with respect to the radius of the hub 73. The outer ends of the ribs 75 join the periphery of the head 71. The formation of the nozzle head 71 cooperating with the shields 72 cause the water being discharged into the washing machine to assume the shape of a stream of S-shaped configuration which is very efficient for cleaning articles in the washing machine.

Transversely across the casing 29 is a tapered bore 77 in which is rotatably seated the drain valve plug 78 having a central opening 79 in registry with the drain passage 30. The valve plug 78 is formed with a lateral reduced stem 80 which rotates in a screw cap 81 which cap closes the open end of the bore 77. Embracing the stem 80 is a coil spring 82 which bears on the plug valve 78 and the screw cap 81 for the purpose of holding the plug securely in the bore of the casing 29. It will be noted that the inner end of the bore 77 is closed thereby providing a unique construction that can leak only at one end. To operate the plug valve 78 I provide a handle 83 secured to the stem 80 by the screw 84.

From the foregoing description of the construction of the circulating system it will be understood that dirty water may be drained through the passage 30 when desired to replenish the water. Water is circulated by centrifugal force from the impeller 47 through the discharge conductor indicated generally at 55 and the water is discharged downwardly over the articles in the basket B to be washed. Water is drawn from the bottom of the container or tub A through the screen 33 and passage 31 and driven by centrifugal force through the discharge conductor 55.

Having described the invention, what is claimed as new is:

1. A washing machine comprising an open top container for washing liquid and articles to be washed including end, side and bottom walls, one of said end walls formed with an opening and the other carrying a handle, a bracket mounted on the said one end wall terminating in a handle, a motor carried by the bracket, a casing secured to the said one end wall and formed with dual passages one above the other in registry at their inner ends with said opening, said casing formed with an impeller chamber in communication with one of the passages, an impeller disposed on a vertical axis mounted in the chamber and oper- 75

atively connected with the motor, and a discharge conductor connected at one end with the impeller chamber and terminating in a nozzle over the container, said discharge conductor connected at 5 an intermediate point with the bracket whereby said conductor is supported, the other of said passages providing a drain for the casing.

2. A washing machine comprising an open top container for washing liquid and articles to be washed including end, side and bottom walls, one of said end walls formed with an opening and the other carrying a handle, a bracket mounted on the said one end wall terminating in a handle, a motor carried by the bracket, a 10 casing secured to the said one end wall and formed with dual passages one above the other in registry at their inner ends with said opening, said casing formed with an impeller chamber in communication with one of the passages, an impeller disposed on a vertical axis mounted in the chamber and operatively connected with the motor, a discharge conductor connected at one end with the impeller chamber and terminating in a nozzle over the container, said discharge conductor connected at an intermediate point with the bracket whereby said conductor is supported, the other of said passages providing a drain for the casing, and said discharge conductor formed with a swivel joint above the bracket for swinging the terminal thereof over the open top of the container, 15

3. A washing machine comprising an open top container for washing liquid and articles to be washed including end, side and bottom walls, one of said end walls formed with an opening and the other carrying a handle, a bracket mounted on the said one end wall terminating in a handle, a motor carried by the bracket, a casing secured to the said one end wall and formed with 20 dual passages one above the other in registry at their inner ends with said opening, said casing

formed with an impeller chamber in communication with one of the passages, an impeller disposed on a vertical axis mounted in the chamber and operatively connected with the motor, a discharge conductor connected at one end with the impeller chamber and terminating in a nozzle over the container, said discharge conductor connected at an intermediate point with the bracket whereby said conductor is supported, the other of said passages providing a drain for the casing, 25 said discharge conductor formed with a swivel joint above the bracket for swinging the terminal thereof over the open top of the container, and said casing equipped with a valve disposed across the other of said passages to control the same whereby spent wash water is drained from the casing.

4. A washing machine comprising a container formed with an opening in one of its walls in the lower portion thereof for the passage of washing fluid, a single casing secured to the container surrounding the opening and equipped with a valve controlled drain passage and a separate inlet passage for the circulation of the fluid and both of which passages communicate directly at 25 one end with the opening in the container, said casing further provided with an open impeller chamber communicating with the other end of the inlet passage, a cover for the impeller chamber detachably connected with the casing, an impeller mounted in the chamber, an impeller shaft connected with the impeller and journaled in the cover, a discharge conduit communicating with the impeller chamber and terminating above the container in a nozzle, a motor operatively 30 connected with the impeller shaft, and a motor mounting means carried by the container and engaging the discharge conduit for supporting the motor and discharge conduit.
